[57] CLAIM

The ornamental design for a table, as shown and described.

DESCRIPTION

FIG. 1 is a top perspective view of a table, showing my new design;

FIG. 2 is a top view thereof;

FIG. 3 is a bottom view thereof;

FIG. 4 is a side perspective view of a table showing my new design; and

FIG. 5 is an end elevational view, the opposite end being identical thereto.
